BLOOD DONOR ASSEMBLY

John Q. Adams, Rutherford, N. J., and Joseph J. Kleiner, Woodmere, N. Y., assignors to Becton Dickinson and Company, Rutherford, N. J., a corporation of New Jersey

Application November 29, 1951, Serial No. 258,942

2 Claims. (Cl. 128—214)

1

This invention relates to a structurally and functionally improved assembly used in connection with blood donation and transfer; the present assembly being also capable of use with liquids other than blood and certain of the elements thereof being useful apart from the assembly. The present application is a continuation in part of our earlier application for patent filed in the United States Patent Office on May 15, 1951, and identified under Serial No. 226,462.

It is an object of the invention to furnish apparatus of this nature and in which a sterile assembly will be instantly available for use. After such use (which may involve either a single operation or a series of steps) the apparatus may conveniently be discarded if it is impracticable or undesirable to clean and sterilize the parts of the same for reuse.

An additional object is that of providing a cannula or needle as part of the assembly; this unit being capable of a ready manipulation although it may at all times, when not in use, be maintained in a housed or protected condition.

Still another object is that of designing an assembly which may be readily and economically manufactured; the several components of the assembly being capable of ready connection to each other to furnish a unitary apparatus which may be employed with facility.

With these and other objects in mind, reference is had to the attached sheets of drawings illustrating practical embodiments of the invention and in which:

Fig. 1 is a sectional side view of the upper end of a sealed container and showing the penetrating cannula moved to a point adjacent to same;

Fig. 2 illustrates the cannula prior to its seal penetration;

Fig. 3 shows the cannula extending through the seal;

Fig. 4 illustrates the manipulation of the cannula assembly after its removal from the seal;

Fig. 5 is a sectional side view of an alternative structure and illustrating a vena needle associated therewith;

Fig. 6 is a perspective view of the entire assembly but showing an alternative form of hub design as well as a manipulating plate;

Fig. 7 is a fragmentary perspective view showing the manipulating plate detached from the cannula hub;

Fig. 8 is a sectional side view of a puncture needle assembly;

Fig. 9 shows a holder preferably used with this assembly;

2

Fig. 10 is a side view of the holder with the assembly mounted thereon and in process of application to a receptacle;

Fig. 11 is a fragmentary view of the receptacle and needle assembly with the blood in course of transfer to the receptacle;

Fig. 12 shows in section one form of tube mounting;

Fig. 13 is a transverse sectional view taken along lines 13—13 of Fig. 12; and

Fig. 14 illustrates another form of mounting.

Considering the seal-puncturing needle, the numeral 10 indicates a cannula provided at its outer end with a penetrating point. The opposite end of the needle furnishes a hub structure conveniently embracing a flange portion 11 and a gripping portion, which, as in Figs. 1 to 4, may be in the form of a truncated cone 12 having its outer face formed with a series of grooves 13. The flange 11 is separated from the conical portion 12 by a neck 14 integral with both of these parts. The entire hub assembly is, of course, secured in any desirable and acceptable manner against movement with respect to the cannula 10. The latter projects beyond the rear of the hub assembly. As shown in Fig. 5 and subsequent views, the truncated cone formation may be superseded by a hub structure 12' of generally cylindrical configuration.

That end of the cannula which extends forwardly of the hub assembly is enclosed in a sheath or cap 15 formed of rubber or any other proper material. The length of the cap should be in excess of the enclosed needle portion. The outer end of the cap is sealed as at 16. Its opposite end is mounted against detachment from the hub assembly by conveniently extending over the flange 11 into the groove provided by the reduced neck portion 14. The rear end of the cannula is ensheathed by the end of a tube 17. The latter is preferably a vinyl plastic tubing and has a normal bore diameter substantially identical with the bore of needle 10. The end edge of the tubing may abut the outer end of the gripping portion.

Now considering the intravenous needle shown in Fig. 5, it will be noted that the body of the same is indicated at 18. This needle is provided with the usual pointed outer end portion. At a point suitably spaced from this end it is encircled by a hub assembly. The latter preferably includes a flange 19 and an enlarged rear portion 20 provided with a groove 21. The flange 19 and rear portion are connected by an integral reduced neck portion 22. The end of tubing 17

opposite to that mounting needle 10 is connected to the portion of cannula 18 which projects rearwardly of its hub assembly. The bore of cannula 18 is preferably the same diameter as the bore of cannula 10. Therefore, in effect a continuous uninterrupted passage of constant diameter will extend from the pointed end of one needle through to the pointed end of the second needle.

Needle 18 is preferably protected by being enclosed in a sheath or cap 23. The latter may be formed of any suitable material such as vinyl tubing. Its length is such that it conveniently extends substantially beyond the pointed end of needle 18 when its opposite end extends into the reduced neck portion 22 and encloses flange 19. The outer end of the sheath 23 may be obstructed by a plug 24 conveniently of cotton and saturated with alcohol if desired.

As is well understood by physicians and other skilled personnel, it is customary to extend one needle of a set into the vein of the donor. The opposite needle of that set is caused to penetrate a seal for a container, the interior of which is conveniently evacuated. Such a container has been shown in Figs. 1 and 6 and indicated by the reference numeral 25 which may mount a protecting cap (not shown). It is provided with a neck portion conveniently furnished with an outer thread 26. The mouth or bore of this neck is sealed by a stopper embracing a body 27 and a head 28. This stopper may be formed of rubber or other proper materials but in any event should embody resiliency. It is provided in its upper and lower faces with aligned recesses 29 and 30 as well as 31 and 32. The bases of these recesses are separated by partitions or diaphragm portions 33 which are relatively thin and disposed in a zone such that they will lie below the pouring lip of receptacle 25 when the stopper is in fully seated position. So seated, that stopper will be under radial compression. Therefore, any perforations of minor size through the diaphragm portions will substantially seal upon withdrawal of the needle which has perforated them.

As heretofore described in connection with Fig. 5 the hub shown in the lower portion of that figure is associated with the intravenous needle. A similar hub may be associated with the stopper-perforating needle 40 as shown in Figs. 6 and 7. Thus, in these figures the numeral 34 indicates a hub portion formed with a groove 35 and a reduced part 36 over which the inner end of the sheath or cap 37 is ensheathed. A plate 38 formed with a notch 39 may be provided as part of the assembly. This notch has extending into it detent fingers 42, the ends of which are curved inwardly and rearwardly and are separated a distance less than the diameter of the base of groove 35. Accordingly, the hub of the needle 40 may have its groove aligned with these fingers and be pressed rearwardly. It will cam against the fingers and due to the resiliency incorporated in the latter they will be spread apart to a point at which the maximum diameter of the hub groove has passed beyond their most closely separated faces. So positioned, the hub of the needle will be retained in association with the plate and the latter will serve as a manipulating portion to permit the operator to force the needle to penetrate the stopper or to withdraw that needle from such stopper.

In this manner no difficulty will be experienced in furnishing a gripping portion permitting of the ready manipulation of this needle. As is obvious the plate may readily be detached from the

needle hub whenever desired. Also as shown in these views the hub of the intravenous needle 41 may, if desired, be plain or knurled. The hub will provide a manipulating part for that needle.

5 The two needles are connected by tubing 17 as heretofore described in connection with Fig. 5.

It will be understood that the parts of this assembly are manufactured in accordance with acceptable procedures. They are cleaned, sterilized and assembled. So assembled an apparatus is furnished in which all essential parts are adequately protected against contamination. In packaging, if a surplus or an inadequate amount of air is present then in effect a "breather" provision is afforded by the tube 23 through the plug 24. At any time the physician or other technician desires to employ the apparatus it will be instantly available for use. All that will be necessary is for the user to remove the assembly from its package and if a receptacle such as 25 is to be employed, to remove the cap or other covering (not shown) which maintains the sterility of the upper surface of stopper 27. Beyond this the procedure will be as follows:

The site of the vena puncture is selected and the surface is sterilized in accordance with acceptable technique. If employed, the sheath 23 is stripped from the needle 18 or 41 and that needle is inserted into the vein. Due to the normal pressure of blood in the vein and the compressibility of air the blood will flow through the bore of cannula 18 and into tube 17, a distance of around 4" to 5". Because of the translucent nature of tube 17 this will be readily apparent to the user. No clamp will be necessary to prevent the blood from flowing into the tube 17 to a greater length or height because air may not escape from needle 10 and sheath 15. Of course if a sheath or its equivalent is not employed, then any suitable clamping structure or provision may be resorted to when it is desired to prevent a flow of liquid through the assembly. Due to the relatively small bore sizes involved, the assembly will function as a metering structure to prevent too rapid a discharge of blood from the vein of a donor. Therefore, no valving mechanism will have to be associated with the needles or tube.

With the removal of the covering from the neck of receptacle 25 the sterile face of stopper head 28 is exposed. If desired, that face may be further sterilized. In any event if the assembly embraces the parts as in Figs. 1 to 4 and with cap or sheath 15 in position on the needle as shown in Fig. 1, the point of that needle is brought to a position overlying diaphragm 33 at the base of recess 29. Cap 15 will not enter that recess. Rather, it will tend to fold or extend angularly with respect to the axis of needle 18 as shown in Fig. 2. Therefore, continued pressure upon the hub of the puncturing needle will force the point of that needle to penetrate the sheath 15 and to thereupon penetrate diaphragm 33. Under these circumstances the cap will in effect be collapsed as shown in Fig. 3. During this projection of the parts it is apparent that if a conical hub portion 12 is provided, the operator's fingers will easily grip the same and be able to force the parts to the desired positions. So shifted they will remain in those positions because the resiliency of the sheath 15 under which it seeks to reestablish its initial position, will be far less than the resistance to movement which occurs due to the frictional contact between the outer face of cannula 10 and the surfaces of the diaphragm 33. Hub portions 12 or 12' (Fig. 5) will also serve as manipulating

parts to permit of the withdrawal of the needle from the position shown in Fig. 3 to that illustrated in Fig. 4. In the latter figure, it will be observed that the fingers of the operator may grip the end of the cap or sheath and stretch the same. Under these circumstances, the point of the needle will withdraw from the perforation in the cap and be completely housed and substantially sealed within the latter. Where a plate 38 is employed, it may readily be coupled with a 10 needle such as 40 to permit of manipulation of the latter.

As will be understood, when the point of needle 10 penetrated cap 45 the bore of the cannula was exposed to atmospheric pressure. Therefore, under the pressure within the vein, the blood was free to rise or flow within tube 17 from needle 48 towards needle 40. Immediately after puncturing the cap or sheath 45 the point of needle 48 penetrated diaphragm 33 at the base of recess 29. Therefore, before blood was discharged from needle 10 the end of that needle was in communication with the interior of the vessel 25 as shown in Fig. 3. The body of that vessel being under vacuum, the flow of blood would, if anything, accelerate through the tube 17. The parts are left in these positions until a desired amount of blood has been taken. When this has occurred, either by grasping the needle hub, or using a plate such as 38, needle 10 or 40 is withdrawn from association with the stopper or other seal. Diaphragm portion 33 being under radial compression it follows that the perforation in the latter will be self-sealing. When cap 45 has been manipulated as in Fig. 4, needle 10 is enclosed in the cap. If desired, a series of tubes or other receptacles may now be employed for the purpose of taking terminal blood samples. These are conveniently closed by stoppers similar to that afore described. It will be understood that if any substantial delay is encountered in taking these samples the enclosing of needle 10 by the cap will prevent coagulation or leakage.

In taking terminal blood samples it is, of course, not necessary to enclose needle 10 within the cap or sheath in the manner shown in Fig. 4 if an undesirable time interval does not elapse. However, in addition to protecting that needle from contamination the cap will—as afore brought out—prevent continuing discharge of blood from the vein when such cap encloses the needle. Upon the conclusion of the operation, needle 10 is withdrawn from the final stopper or seal. Thereupon needle 18 is withdrawn from the vein. As will be appreciated by employing tubing 17 of the character described hemolysis is prevented. This will be because in effect a single continuous passage free from constriction and enlargements is provided from the outer end of one needle through to the outer end of the second needle. Therefore, the blood in flowing through this passage will not be buffeted and subjected to accelerated as well as retarded flows with consequent detriment to the blood discharged into receptacle 25 or other receptacles. The purpose of recesses 31-32 and any other recesses through the stopper 28 will be apparent in that one or more vents, tube connections or other expedients may thus be provided and by means of which the contents of the receptacle may be caused to flow as desired. As will finally be understood, the tubing connecting the two needles is preferably formed of that type of plastic which when stretched tends to return to its normal position. Therefore, a tight seal is provided between the 70

needles and the tubing. Additionally, the bores of all three are substantially constant throughout the entire assembly. The shrinking of the tube into contact with the rear needle surfaces may be assisted by employing heat if desired.

In Figs. 8 to 11 an alternative and in certain respects preferred form of structure has been illustrated. Referring primarily to Fig. 8, it will be seen that the stopper-penetrating needle or cannula 40 may be enclosed in a sheath of protective material 41. This sheath or cap is conveniently provided by a suitable plastic which will have resiliency such that its open end constricts around and frictionally engages those portions of the cannula assembly which are adjacent the hub. The latter as afore described is formed with a groove which in these views have been indicated by the reference numeral 42. As previously taught, the rear end portion 43 of the cannula is connected by a tube 44 with the vena needle.

A needle manipulating holder and clamp has been shown in Figs. 9 and 10. This is conveniently formed of metal and includes a base plate 45 formed with a notch 46. In common with the notch structure heretofore described in connection with Figs. 6 and 7, arms preferably extend into this recess at a point such that the grooved portion of the needle may be inserted into the notch and removed therefrom. When inserted the needle will be retained as a unit with plate 45 and against any probability of accidental detachment. Extending upwardly from this plate is a portion 47 formed with a slit 48. The outer end of the latter has its edges diverging and separated a distance such that tube 44 may readily be accommodated therein. When this tube is moved downwardly into the slit it is pinched or constricted to a point where no flow of fluid may occur through it. Due to the restricted series of bores which provide the conduit for the flow of blood that flow will be metered so that there will be no danger or discomfort on the part of the donor. The straight edge portions of the slit 48 will assure that there will be no tendency of the tube to accidentally ride out of the slit. As shown the plate adjacent the slit may be reduced as indicated at 49. This reduction in thickness will assure that the edge portions defining the slit are sufficiently narrow so that while a proper clamping action may occur between them and the surface of the tube, too great a frictional contact between these parts will not occur. The stopper-penetrating needle together with the holder have been shown with the sheath removed in Fig. 10. Also, in that view tube 44 has been shown in a position within the slot where it is properly constricted.

In using an assembly of this nature needle 40 has the grooved portion 42 of its hub inserted into notch 46. A portion of tubing 44 adjacent this cannula would then be disposed within the slit 48 and wedged by the edges of the latter so as to prevent any flow of fluid through tube 44. Thereupon, if cap 41 is used it may be removed and plate 45 is grasped between the thumbs and index fingers of both hands. By exerting a steady straight pressure down on the selected site of stopper 49 the latter will be penetrated by the needle. The receptacle 50 which is sealed by this stopper may, in common with the receptacle 25, contain any desirable material such as acid citrate dextrose. This will act as a preservative, anticoagulant and feeding agent for the blood. The receptacle 50 is now inverted as indicated in

Fig. 11 and properly supported. When the vein has been punctured by the needle connected to the opposite end of tube 44, that tube 44 is removed from clamping engagement with the slit or slot 48. Plate 45 may now be detached from the needle. Under these circumstances blood will flow to the receptacle. Such flow will be accelerated incident to the vacuum existing within that receptacle. However, as indicated in Fig. 11, the blood will merely bubble to the surface of the body of liquid 51 within the same and will not spurt into contact with the receptacle surfaces, upon which it would tend to coagulate. A lack of spouting will be because, with a metered flow and substantial constant bore existing from the vena needle through to and including the stopper-penetrating needle, there will be no tendency for the latter to act as a nozzle and for surges to occur within the tube assembly.

After the desired quantity of blood has been withdrawn tube 44 is again disposed in clamping relation with the edges of slit 48. Holder plate 45 has its notch arranged in line with groove 42 and by lateral movement the needle is coupled with that holder. By placing the index finger of each hand under the opposite ends of the plate a gentle steady pull may be exerted to withdraw the needle from the stopper. The latter as afore brought out is preferably self-sealing. The holder may remain on the needle until terminal bloods are taken. After this operation has been completed the intravenous needle is withdrawn. The holder is removed from the needle 49 and the latter together with its connected tube and vena needle are discarded.

In the several forms of apparatus as illustrated it is preferred that the internal diameter of tube 17 or 44 be on the order of .05". By employing a tube having this bore size with needles of customary gauge, very satisfactory results are achieved. In the average case and employing a receiving receptacle of accepted capacity, the bleeding time runs between four and a half and seven minutes. A separate metering structure is unnecessary in that the bore sufficiently controls the flow in a manner entirely satisfactory.

To prevent an accidental detachment of tubing 17 from the rear of the needle, a sleeve 50—as in Fig. 5—may be provided of plastic or other suitable material. This sleeve has a bore incorporating a diameter such that it may freely receive the tubing in its initial state. However, where that tubing is expanded over the rear of the needle 10 it will be intimately engaged by the sleeve bore. This will prevent any relative and accidental movements between that needle and the tube portion mounted thereby. If, instead of threading the sleeve on the tube it is desired to mount the former by lateral movement, it may be slotted as at 51' in Fig. 5, the width of this slot being less than the exterior diameter of the tube. Thus, the sleeve may be moved laterally so that the tubing passes similarly to the structure at 50, it may be shifted axially to the position shown. In both instances the sleeve—in addition to constricting the tubing around the rear portion of the cannula—will provide a guard preventing the fingers of the operator from axially compressing the tubing to enlarge its bore diameter. Accordingly, the danger of accidental detachment of the needle from the tube is reduced.

Alternative structures in this connection are shown in Figs. 12, 13 and 14. In the first two views a needle has been shown at 52 which is

provided with a hub 53 having a rearwardly tapered surface 54 and an extended portion 55 beyond the same. The tube 17 is mounted upon this portion and a split sleeve 56 is applied to the parts in the manner described in connection with sleeve 51'. The sleeve 56, having bevelled entrance portions 57, will wedgingly engage tapered surface 54 and thus be firmly mounted to act as a guard.

As in Fig. 14, the needle 58 may be provided with a hub 59 beyond which a threaded portion 60 is disposed. In that instance the sleeve 61 has its opposite end provided with corresponding threads. Therefor, this sleeve may also be fixedly mounted by the needle assembly. These sleeves may be formed of metal or other suitable material. As shown, they may be slotted. If desired they might incorporate dimensions such that their bores engage part of the exterior surface of the tubing ensleeved over the rear cannula end. Thus, in addition to functioning as guards, they would serve to further restrain movement of the mounted tube portion with respect to the needle.

Thus, among others, the several objects of the invention as aforesaid are achieved. Obviously numerous changes in construction and rearrangement of the parts might be resorted to without departing from the spirit of the invention as defined by the claims.

We claim:

1. In an assembly of the character described a needle mounting and manipulating plate, said plate being formed with a needle-receiving notch and resilient detent arms extending from said plate into said notch and separated a distance such that they cooperate with the hub portion of a needle disposable in said slot.
2. In an assembly of the character described a plate to be secured to a needle, an upwardly projecting extension forming a part of said plate, said extension being formed with a slit defined by spaced side edges to receive between them and constrict a tube connected to a needle and the thickness of said plate adjacent such edges being reduced.
